OTHER PUBLICATIONS

U.S. Appl. No. 12/718,517, Vestuti et al., "Lacrosse Stick and Head", filed Mar. 5, 2010.

Primary Examiner — Mitchell Siegel(74) *Attorney, Agent, or Firm* — Sterne, Kessler, Goldstein & Fox P.L.L.C.(57) **CLAIM**

The ornamental design for a lacrosse stick, as shown and described.

DESCRIPTION

FIG. 1 is a rear view of a lacrosse stick showing our new design;

FIG. 2 is a rear perspective view thereof;

FIG. 3 is a front view thereof; and,

FIG. 4 is a front perspective view thereof.

The broken lines in the Figures show environment for illustrative purposes only and form no part of the claimed design. The dot-dashed lines in the Figures show an indeterminate border around portions of the subject matter being claimed.
